John Shaw's Snow Cutter
Spencer Patent

The subscriber desires to inform Letters Patent and make part of the same containing a description in the words of the said John Shaw himself of his improvement in the Snow Cutter.

To all to whom these Presents shall come

Be it known that I John Shaw of the City & County of Philadelphia in the State of Pennsylvania have invented a new and useful improvement in the Snow Cutter & that the following is a full & exact description of the construction and operation of the said machine as invented aforesaid by me, my

A. The box, this made in the usual form the bars and being want stand-
ing higher than the front one being supported by posts & a gate, having a piece
of board fastened on the top of said box near the front end, also a strip
of steel placed on the inside of said box over the front end for the knife
to pass close to it. B. The gate, this framed together with girts, an iron
bar being placed in the middle for the front of said box to rest against
and a iron bar being placed on each side of said box & projecting out beyond said box, having
each grooves for the tongue of the gate to fit in. C. The knife, this
is made of steel being cut on the edge & upon the concave edge, having
holes near each end to screw it on across the back side of the gate at an
angle of about forty degrees. The places that when the gate works up & down
the said sharp edge will pass close by the edge of said steel. D. The gate,
this is made of iron having on the outside of each largest part a tongue
to fit in the grooves in said post & a handle screwed on the front side of
said gate to work it up & down. The said gate has a board having a
curved on the outside on the lower part of said gate that can be turned
out to gauge the length of the snow to be cut, not coming quite
up to the said knife. The top part of said lower end of said gate
to be taken off with the hand saw. The advantage of this improvement are
that the cutting of the snow is more rapidly, requiring but the work of
one man to do it.

John Shaw
